UNITED STATES PATENT OFFICE.

CLARENCE A. WARREN, OF LE ROY, MICHIGAN.

BALING-PRESS.

1,206,182.

Specification of Letters Patent. Patented Nov. 28, 1916.

Application filed November 15, 1915. Serial No. 61,702.

To all whom it may concern:

Be it known that I, CLARENCE A. WARREN, a citizen of the United States, residing at Le Roy, in the county of Osceola and State of Michigan, have invented certain new and useful Improvements in Baling Presses, of which the following is a specification.

My invention relates to improvements in presses for baling waste paper, rags, and other packages that are to be made up into bales for convenient shipment, and its objects are: first, to provide a convenient and easily worked baling press without the use of gear wheels, pawls and ratchets, and kindred surplus mechanism, and, second, to provide a baling press that may be easily and readily opened and closed and otherwise manipulated for entering and removing the article to be baled, and the bales after they have been properly pressed and bound. I attain these objects by the mechanism illustrated in the accompanying drawing, in which—

Figure 1 is a perspective of the press in its normal position, with both doors closed; Fig. 2 is a front elevation of the press with the upper door opened to show the manner of hanging the press head on the actuating shaft, and Fig. 3 is a like view with both doors open showing the internal construction of the press.

Similar numerals refer to similar parts throughout the several views.

In the accompanying drawing 1 represents the sides of the press; 2 represents the upper door; 3 represents the lower door, and 9 represents the base of the press.

The upper door 2, and the lower door 3 are hinged together, as at 4, so the upper door may be opened from the top outward and downward, as indicated in Figs. 2 and 3, and the lower door is hinged to one side, 1, of the press, as at 10, 10 so it may be opened sidewise, as shown in Fig. 3.

12 represents a hasp by means of which the lower door 3 may be secured in its closed position.

The sides 1 of the press are slotted, as indicated at 11 in Fig. 1 so the actuating shaft 5 may be readily raised and lowered therein. This shaft is revolvably secured to the girt 15 that supports the press head 16, by means of any available form of connecting element, as the staples 14, shown in Fig. 3. It

will be readily understood that any upward, 55 or downward movement of the shaft 5 must carry the press head 16 with it.

My device for raising and lowering the shaft 5, and with it the head 16, consists of ropes, or cables 7, 7, securely attached at one end to the plate 8, thence passing downward and wound several times around the ends of the shaft 5, as at 12, 12, and thence extending downward, drawn very tight and the other ends securely connected with the base 60 9. If it is deemed necessary to provide against the danger of the shaft turning within the folds of the ropes 7, 7 it may be accomplished by passing one fold of the ropes through the shaft, as indicated at 12' 65 in Fig. 1, and providing a sufficient number of circles of rope around the shaft to provide for the distance the shaft and head must be raised and lowered. I provide for revolving the shaft 5 by means of levers or 70 rods, 6. One or two may be applied, as may seem necessary or desirable. It will be readily understood that if the shaft 5 is made to revolve over toward the front of the press the action of the ropes thereon will draw the 75 head 16 forcibly downward upon the material or goods in the press to be baled, and if the revolving movement of the shaft is reversed the head 16 will be drawn upward 80 away from the baled goods.

The upper end of the lever 6 is placed back of the girt 8 to avert the danger of the weight of the head 16 causing the shaft to revolve and allow the head to drop downward in inconvenient position when the 85 goods are being placed in the press.

The back, 13, is made of plank that are secured to the top and base of the machine, permanently, in the usual manner of forming the sides, backs and ends of this class 90 of presses.

What I claim as new, and desire to secure by Letters Patent of the United States, is:—

1. In combination with the case, base, plate and pressure head of a baling press, a 100 shaft revolvably mounted directly upon the pressure head and extending outward beyond the sides of the case, a rope secured to the ends of the plate at each side of the case, extending downward and wound several 105 times around the ends of the shaft, and thence extending downward and the other ends securely connected with the base, and

a lever connected with the shaft for revolving the shaft to raise and lower the pressure head.

2. In combination with the case, base, 5 plate and pressure head of a baling press, the sides of said case having slots there-through, a shaft revolubly connected with the pressure head with its ends extending through the slots in the sides of the case, a 10 rope at each side of the case having one end securely connected with the ends of the plate and the other ends securely connected with the base, the bodies of said ropes wound several times around the ends of the shaft, 15 means for preventing the shaft from slipping in the coils of the rope, and a lever for revolving the shaft to raise and lower the

pressure head by the action of the shaft upon the coils of the rope.

3. In combination with the case, base, 20 plate and pressure head of a baling press, the sides of said case having slots there-through, and doors upon the case, a shaft revolubly mounted on the pressure head with its ends extending through the slots in the 25 sides of the case, a rope so connected with each end of said shaft, and with the base and plate of the press that the revolving of the shaft will cause the pressure head to raise and lower.

Signed at Le Roy, Michigan, November 8, 1915.

CLARENCE A. WARREN.
